UNITED STATES PATENT OFFICE.

ALFRED BEAMER, OF SPOKANE, WASHINGTON.

METHOD OF OPERATING RAILWAY-TRAINS.

No. 927,401.

Specification of Letters Patent.

Patented July 6, 1909.

Application filed May 9, 1908. Serial No. 431,939.

To all whom it may concern:

Be it known that I, ALFRED BEAMER, a citizen of the United States, residing at Spokane, in the county of Spokane and State of Washington, have invented certain new and useful Improvements in Methods of Operating Railway-Trains, of which the following is a specification.

The object of my invention is to provide a method of controlling the movements of railway trains, whereby a higher degree of safety will be obtained and the capacity of the road increased.

The particular nature of the invention and the points wherein it differs from methods now in vogue will clearly appear from the following description and claims.

In the drawings—Figure 1 represents diagrammatically one division of a single track railway. Fig. 2 represents a blank form designated a "block card". Fig. 3 is a view of the rear of a train with the mechanism for delivering despatches thereto. Fig. 4 is a view of a despatch hoop.

While the drawing illustrates my invention applied to a single track provided with the usual sidings, it will be obvious that the invention is equally applicable to a double track system or a system provided with more than two tracks.

Before proceeding to a description of my method I will briefly refer to the mechanism which I preferably employ therewith, although it will be understood that the invention herein claimed resides in the method and is independent of the particular instrumentalities employed for carrying it out.

In carrying out my invention I divide the line into blocks and employ a through telegraph or telephone wire extending from the train despatcher's office throughout the length of the division, by which communication is established between the train despatcher and the operators at the various block stations, and local telegraph or telephone lines between each block station.

Referring to Fig. 1 of the drawings, the main track is designated by the numeral 1 and is provided with lap sidings 2 at each station. Fig. 1 is intended to represent a single division of a railroad extending between the stations Lewiston and Marshall, which division is divided into three blocks by the block stations Garfield and Plaza. A telegraph or telephone line 3 extends from

the train despatcher at Marshall throughout the length of the division and is provided with branches 4 extending into each block station. By this means the train despatcher can call up and communicate with the operators at any of the stations. Independent telegraph or telephone lines 5, 5^a and 5^b extend between adjacent stations, whereby each operator can communicate with the operator at the end of the block on each side of his station. The main line 3 is reserved for communication between the despatcher and the several operators, while communication between the operators themselves is restricted to the local lines 5, 5^a and 5^b.

Each station is also provided with semaphore and disk signals 6. These semaphores are composed of a post or mast to which are attached two sets of arms and two sets of disks, one set of both on each side of the post or mast as viewed from an approaching train, and the movement of the approaching train is governed by the position of the semaphore arm or disk on the right side of the mast as viewed from such train. The semaphore and disk signals, as I prefer to operate them, have the following significance: The horizontal position of the governing arm of the semaphore, or a red light, is known as a stop signal and indicates that the block is not clear. A diagonally downward position of the semaphore arm, or a green light, are known as the clear signals and indicate that the block is clear. A diagonally upward position of the semaphore arm, or a yellow light, indicates that the train from which it is seen is to take siding to meet or be passed by another train.

In those cases where the home semaphore, that is, the semaphore located opposite the block station, is visible for only a short distance, I provide distant semaphores, the distant semaphores displaying only two signals and having the following significance: The semaphore arm being positioned diagonally upward or displaying a yellow light indicates that the approaching train is to take the siding for the purpose of being met or passed by another train. The semaphore arm being directed diagonally downward, or displaying a green light, indicates that the block is clear and directs the engineer to proceed to the home semaphore, whereupon his movements will be governed by the receipt of written orders or block cards— as

hereinafter described. In no instance is the passage of a train through a block dependent upon the semaphore or disk signals, these signals being merely indicative of the nature of the orders to be delivered to the train at the block station, and until such written orders are received the train has no right whatever in the next block.

I will next briefly describe the mechanism whereby the written orders, or block cards, are delivered to moving trains, confining my description to the general nature of the apparatus, for the reason that its detailed construction forms no part of the method herein claimed. As illustrated in Fig. 1 of the drawings, I provide at each block station a mast 7 provided with means for detachably holding at different elevations two of the despatch hoops 8 shown separately in Fig. 4 of the drawings. The despatch holders consist of a hoop preferably made of wood and provided with a projecting stem adapted to engage the spring holder mounted upon the mast 7. A suitable spring clamp is provided for holding the despatch or block card 9 upon the hoop in the position shown in Fig. 4. The masts 7 are erected near the track and so arranged that the hoop projects therefrom toward the track and lies in a plane at right angles to the track. Upon the locomotive, and rear car of the train, are mounted projecting arms 10, as shown in Fig. 3. In operative position, the arms or catchers 10 project forward diagonally from the car side and are so positioned that one of them enters the lower and the other the upper hoop, thus detaching it from its holder and carrying it along with the moving train. The catchers 10 are, preferably, so constructed that they may be folded against the side of the locomotive or car when not in use. I provide means for delivering two despatch hoops, one to the catcher on the locomotive and the other to the catcher on the rear car, for the reason that it is necessary to deliver the orders in duplicate to the conductor and engineer.

Having now briefly described the mechanism which I preferably employ in carrying out my method, I will proceed to a description of the method itself, first referring to the system of operation now generally in vogue for the purpose of distinguishing my invention therefrom.

As is well-known, trains upon American railroads are now ordinarily operated by means of time-tables, such tables containing schedules of the time at which trains depart from the different stations upon the railroads, and in some instances both the arriving and departing time. While an extended description of this system is unnecessary, brief reference will be made to some of its leading characteristics in order to better dis-

tinguish my invention therefrom. In addition to the time-table system now in vogue, a complicated set of rules is necessary in order to provide for the numerous instances in which circumstances prevent the trains from adhering to the running time set forth in the time-tables. For this purpose trains are generally designated as "regular," "extra," and "special," a regular train being one scheduled on the time-table, an extra train being a freight train not scheduled in the time-table, and a special being a passenger train not scheduled in the time-table. Trains are also subdivided as "superior" and "inferior" and one train may be superior to another either by right or by class. A train of superior class is one given precedence by a time-table and a train of superior right is one given precedence by train order. The rights of trains to proceed upon the main track are dependent upon the class to which the train belongs and upon its rights as defined by train orders, and in case a train arrives at a designated meeting or passing point the question as to whether it shall proceed on its way on the main track or take the siding and await the passage of the opposing train is determined by a complicated system of rules defining the precedence of one train over another as determined by its class and rights conferred by time-table and train orders.

From the foregoing brief outline of methods now in vogue, it will be seen that the movement of a train is often dependent upon the interpretation of more or less complicated rules relating to the rights and class of the various trains, thus inviting misunderstandings leading to accidents and causing delays.

The purpose of my invention is to govern all movements of trains by written orders delivered to the conductor and engineer at each block station, such written orders being issued only after communication between the operators at each end of the block to be entered and between the operator at the entrance of the block and the train despatcher of the division. Under my system no time-table whatever will be employed except the usual advertising time-table of passenger trains which will be issued for the use of the public, but without conferring any rights whatever upon the trains therein scheduled.

My system may be most clearly explained by reference to Fig. 1 of the drawings in which the division terminals are Lewiston and Marshall. The division is represented as being divided into three blocks separated by the stations designated Garfield and Plaza. Upon the departure of a train from a terminal, the terminal operator will notify the operator at the end of the first block of that fact, thus enabling him to anticipate

the arrival of the train, and upon the movement of a train past any block station the operator, using the "despatcher's" wire, will notify the train despatcher of that fact 5 and, using the "local" wire, will give the same information to the operators at the adjoining block stations. By this means the train despatcher will be constantly advised of the condition of each block in his division, 10 and each operator will be advised of the condition of two blocks adjoining his station. Furthermore, no operator will be advised of any train movements upon any part of the road other than the two blocks 15 adjoining his station. Each operator's communication is confined, through the local wires 5, to the operators at the ends of the adjoining blocks, and through the despatcher's wire 3 to communication with the train 20 despatcher relative to the condition of the two adjoining blocks. Each operator's transactions therefore are confined to the two adjoining blocks, and all danger of confusion resulting from burdening each operator with a mass of information relative 25 to distant train movements is avoided.

The governing arm of the semaphore—as above stated—is operated from the block office by the operator. The semaphore or 30 other signal, however, confers no running rights upon approaching trains, but merely indicates the character of the orders which will be delivered to the engineer and conductor at the block station.

35 Referring now to Fig. 1 of the drawings, it is assumed that the operator at Plaza has been informed by the operator at Marshall of the departure of a west bound train drawn by engine 1356 from Marshall. 40 I prefer to identify the trains by the numbers of the engines drawing them. Slightly prior to the time at which this train should arrive at Plaza, the operator at that point consults the advices which he has received 45 from the operator at Garfield and his own records, and if he finds that the block between Plaza and Garfield is clear, he calls the despatcher, using the following formula—"B engine 1356", the meaning of 50 which is understood as being that the operator is asking for a block for the train pulled by the engine designated. The despatcher, having previously directed the departure of this train, is already advised of 55 the direction in which it is moving, and having been informed by the operators at Plaza and Garfield of the passage of all trains by their stations, is in a position to determine whether the operator at Plaza is correct in 60 asking for a block for the train referred to. If the information in the possession of the despatcher corresponds with that which led the Plaza operator to make the request, he directs the issuance of a block card, using 65 the following formula—"B. C. No. 24 to

Garfield, O K — time". The number 24 is the serial number of the block card, all block cards issued at the despatcher's office being consecutively numbered daily beginning at 12:01 a. m. as a safeguard against 70 oversight. In Fig. 2 of the drawings, I have illustrated the form of block card which I have adopted in use. This block card is preferably printed upon a quality of paper that may be easily attached by 75 means of the spring clamp upon the hoop shown in Fig. 4 and is provided with blank spaces for the information indicated by the printing thereon. Upon the receipt of this order from the train despatcher, the operator at Plaza enters it upon the block card and places two copies of the same upon the holder 7, whereby one is delivered to the engineer and one to the conductor of the passing train without necessitating a stop. 80 At the same time, the operator sets the semaphore arm diagonally downward or displays the green signal, the normal position of the semaphore being horizontal or red. The engineer of the approaching train, observing the clear signal, is relieved of the necessity of slowing down, but is not given any rights to pass through the next block unless the block card picked up in passing the station confirms the information conveyed by the signal. 85

It will be observed that under the conditions as above outlined it would be impossible for the train referred to to pass the station Plaza and enter upon the block between Plaza and Garfield without the concurrence in the same mistake at the same time by three different people. The Plaza operator cannot under this system ask the train despatcher for a block card to Garfield until all east bound trains which have passed Garfield have also passed Plaza, and until he has been informed by the operator at Garfield that all west bound trains which have passed Plaza have also passed Garfield. 100 Furthermore, the train despatcher will not authorize the issuance of the block card unless his advices from both operators also show that the block in question is clear. Upon the receipt by the Plaza operator of 105 authority to issue the block card for west bound train drawn by engine 1356 he will not only set the signals and put the block cards in position to be caught by the passing train but will also inform the operator at 110 Garfield of the issuance of the block card, the information being preferably conveyed by the following formula—"B. engine 1356", that is, block engine No. 1356. This is interpreted by the operator at Garfield as 115 indicating that a pledge of the block is required from him for the movement of a train toward his station. If the block is clear the operator at Garfield responds, preferably using the following formula—"O. K., 120

S D", signifying that he has displayed his signal in a horizontal position or showing red for the purpose of blocking all tracks going toward Plaza.

5 As before stated, the requirement that all trains get block cars at all block stations is new in railroad operation, and dispenses absolutely with all time-table rights or rights dependent upon classification of trains, and 10 makes the movements of trains absolutely dependent upon the delivery of written orders at each block station, such orders being issued only upon the concurrence of the operator at each end of the block to be entered and the train despatcher.

15 In case the train despatcher, upon receipt of a request for a block card, finds that the request has been improperly made, or that while properly made he desires for some 20 reason to hold the train for which a block card has been requested, he will convey such information to the operator requesting the block card. Such operator will thereupon display either the stop signal or the signal 25 to take siding. It will be seen, therefore, that the system is elastic and permits the train despatcher to give preference to particular trains as occasion demands, but no such preference is given to any train by a 30 time-table, or by any system of classification depending upon the direction of movement or character of the train.

35 As demonstrated in actual use, the adoption of my improved method of operating railroad trains insures the highest degree of safety and at the same time renders it possible to operate from twenty to twenty-five per cent. more trains than under the time-table system. Delays in the operation of 40 trains are reduced to a minimum, as the rigid restrictions due to the use of time-tables and complicated rules based thereon are abolished, and the movement of trains made dependent solely upon the existence of 45 a clear track and such preference as the train despatcher may give to certain trains over others. The fact that the visual signals—semaphores and disk signals—confer no running rights on trains, but merely 50 indicate the character of the written orders to be subsequently delivered, is an absolute preventive of delays or accidents due to failure to read the signals correctly.

55 A further element of safety results from the fact that in the use of my system each operator is concerned only in the movement of trains through the block on each side of him, and has no knowledge of or connection with any block or section of road outside of 60 those two. The train and engine men can receive authority to run only through the block ahead of them, hence there is no opportunity for an operator to misunderstand the nature of the instructions given him by 65 the despatcher and there can be no error

made by train and engine crew as to the next station to which the train is allowed to proceed.

In train operation as now conducted, the operators at way stations are all more or less involved in the system of train orders having reference to stations and blocks at all of the various points on each division. At present an operator may receive an order for a train to meet another train in the opposite direction at his station when the trains involved may be at points fifty or one hundred miles distant, an operation that will not be completed within anywhere from two to three hours, during which time the train and engine crew are required to keep the matter in mind and not overlook it. Practically all the objectionable elements inherent in the present system of regulating train movements are obviated by my improved method 85 of procedure, as above explained. Under methods now in vogue the train despatcher starts a train out with instructions to meet or pass anywhere from one to a dozen trains at as many different stations, and transmits 90 corresponding orders to the operators along the line.

A further source of error inherent in the present system is the necessity for the train despatcher to rely upon his train order book, 95 in which he inscribes the orders issued by him, and his train sheet for the purpose of regulating the movement of trains. The train sheet is a sheet of paper ruled in vertical columns, the center column containing 100 a printed list of the stations on the division of the road to which it pertains. The columns at the sides are reserved for recording the arriving and departing time of the trains in transit. One column is assigned to each 105 train, the columns at the right of the center being assigned to trains moving in one direction and those to the left being assigned to trains moving in the opposite direction. From this sheet and the position of the 110 trains as indicated by the time they are at the different stations, the despatcher arranges his meeting points for trains in the opposite directions and passing points for 115 trains in the same direction. Three despatchers are usually employed in the same office to despatch trains over the same piece of track, working eight hours each. The man on duty at midnight starts a new train sheet on which he records all trains leaving 12 a terminal after midnight but continues to use, in addition to this new sheet, the sheet of the previous day until such time as all the trains leaving a terminal on the day previous have reached their destinations. The 12 difficulty of arranging meeting and passing points under this system will be readily appreciated.

In carrying out my improved system I prefer to employ a train sheet in which 13

separate strips of paper are used for the printed list of stations and for each of the train records. As each train arrives at its destination or passes out of the division over which the train despatcher has control, its record is removed and replaced either by a blank strip or by one of the incomplete record strips which is farther from the central column of stations. By this means it is never necessary to consult more than one train sheet, and the columns or strips of paper on which trains in transit are recorded may always be kept near the central column of stations, thus avoiding the inconvenience and possibility of error arising from consulting more than one train sheet and from comparing data recorded in widely separated columns on the same sheet.

The expediting of train movements by my improved system results not alone from its freedom from error due to making the movement of trains absolutely dependent upon written orders at all times, as distinguished from a time-table supplemented by train orders, or a system dependent upon visual signals exclusively, but the movement of trains is further facilitated by the delivery of orders, by the means hereinbefore described, to moving trains. An essential principle of my plan of operating trains is the provision that trains shall never be stopped for the delivery of orders. I secure the speed of operation incident to the use of visual signals, the certainty inherent in restricting train movements to written orders, and insure the accuracy of the written orders by necessitating the concurrence of three individuals in their issuance.

I claim:

1. The method of operating railroad trains, which consists in dividing the track upon which said method is applied into blocks separated by block stations, rendering the entrance of all trains into any block dependent exclusively upon the delivery of written orders to the train, and rendering the issuance of such orders dependent upon the block to be entered being shown to be clear by the train records of the train de-

spatcher and of the operators at each end of said block.

2. The method of operating railroad trains, which consists in dividing the track upon which said method is applied into blocks separated by block stations, rendering the entrance of all trains into any block dependent exclusively upon the delivery of written orders to the train, restricting the authority conveyed by each order to permission to pass through a single block, and rendering the issuance of such orders dependent upon the block to be entered being shown to be clear by the train records of the train despatcher and of the operators at each end of said block.

3. The method of operating railroad trains, which consists in dividing the track upon which said method is applied into blocks separated by block stations, rendering the entrance of all trains into any block wholly dependent exclusively upon the delivery of written orders to the train, rendering the issuance of such orders dependent upon the block to be entered being shown to be clear by the train records of the train despatcher and of the operators at each end of said block, and displaying at the block stations visual signals indicative of the nature of the written orders to be delivered to approaching trains.

4. The method of operating railroad trains, which consists in dividing the track upon which said method is applied into blocks separated by block stations, indicating to approaching trains by visual signals the nature of the written orders to be delivered to said trains, rendering the entrance of all trains into any block dependent exclusively upon the delivery thereto of written orders, and delivering such written orders to trains while in motion.

In testimony whereof, I have subscribed my name.

ALFRED BEAMER.
